(57) **CLAIM**

The ornamental design for a case for a wireless networking device, as shown and described.

DESCRIPTION

FIG. 1 is a perspective view of a case for a wireless networking device showing my new design;

FIG. 2 is a rear orthographic view thereof;

FIG. 3 is a front orthographic view thereof;

FIG. 4 is a left side orthographic view thereof;

FIG. 5 is a right side orthographic view thereof;

FIG. 6 is a top orthographic view thereof;

FIG. 7 is a bottom orthographic view thereof; and,

FIG. 8 is a bottom orthographic view thereof, in which environmental subject matter has been omitted in order to more clearly show the claimed design.

The broken lines shown in FIGS. 1–8 are included for the purpose of illustrating environmental elements only and form no part of the claimed design.
